[57] CLAIM

The ornamental design for a hamper, substantially as shown and described.

DESCRIPTION

FIG. 1 is a perspective view of a hamper showing my new design;

FIG. 2 is a front elevational view thereof;

FIG. 3 is a side elevational view of the left side of the hamper as viewed in FIG. 2; the right side of the hamper is a mirror image thereof;

FIG. 4 is a rear elevational view thereof;

FIG. 5 is a top plan view thereof;

FIG. 6 is a bottom plan view thereof; and

FIG. 7 is an enlarged elevational view of the wicker work shown in FIGS. 1 and 2 in the front side top section of the four sections comprising the front side.
